UNITED STATES PATENT OFFICE.

WILLIAM HERMAN SCHILLINGER, OF ROCK ISLAND, ILLINOIS.

EXPLOSIVE-ENGINE.

1,218,214.

Specification of Letters Patent.

Patented Mar. 6, 1917.

Application filed December 15, 1913. Serial No. 806,785.

To all whom it may concern:

Be it known that I, WILLIAM HERMAN SCHILLINGER, a citizen of the United States, residing at Rock Island, county of Rock Island, State of Illinois, have made a certain new and useful Invention in Explosive-Engines, of which the following is a specification.

This invention relates to explosive engines.

The object of the invention is to provide an explosive engine of the internal combustion type which is simple in construction, economical to manufacture and efficient in operation.

A further object is to provide an engine of the type referred to wherein the explosive charge is supplied automatically, or mechanically, and under pressure.

A further object is to provide means for completely evacuating the explosion cylinder of the gases and other products of combustion following an explosion of a charge before the next charge of explosive material is injected into the explosive chamber.

A further object is to discharge the gases of each explosion by the use of compressed air, thereby preventing pre-ignition of the succeeding charge, reducing carbonization, increasing the efficiency of the fresh explosive charge and promoting economy in the fuel required.

A further object is to provide means which are simple, direct and efficient for cooling the interior of the explosion cylinder by the use of a forced fresh air blast in scavenging.

A further object is to provide for the increase of the cubic capacity of the explosion chamber over that of a normal explosion chamber of ordinary types of engines, thereby permitting an increase of the volume of the explosive charge, and consequently increasing the power developed through the greater expansive energy of a larger explosive charge.

A further object is to provide means for reversing the engine and for application of power in the reverse direction of operation without the use of reversing gears or other transmission devices.

A further object is to provide adjustable means, mechanically controlled for actuating the intake valve within the explosion piston.

A further object is to provide means for taking in, compressing and storing air at

each stroke of the engine and utilizing the compressed air to clear the explosion chamber and cylinder after each explosion, and to inject the fresh fuel charge into the explosion chamber and cylinder under pressure, after being first cleared of exploded and used gases and then filled with fresh clean atmospheric air.

Other objects of the invention will appear more fully hereinafter.

The invention consists substantially in the construction, combination, location and relative arrangement of parts all as will be more fully hereinafter set forth, as shown in the accompanying drawings, and finally pointed out in the appended claims.

Referring to the accompanying drawings and to the various views and reference signs appearing thereon,—

Figure 1 is a view in vertical central section showing an explosive engine constructed in accordance with my invention.

Figs. 2 and 3, are views similar to Fig. 1, showing the parts at different points in the stroke of the piston.

Fig. 4 is a top plan view of the piston.

Fig. 5 is a fragmentary view, partly in side elevation and partly in vertical section, showing a portion of the tubular sleeve and relation of port openings with the parts in the position shown in Fig. 1.

Figs. 6, 7 and 8 are detail diagrammatic views respectively indicating the different positions of the crank shaft in Figs. 3, 2 and 1, respectively.

Fig. 9 is a broken view, partly in side elevation and partly in vertical section, showing the casing and the by-passes from the casing to the explosion cylinder, and the relation of the by-passes to admit of change in timing of operation.

Fig. 10 is a view in vertical central section of a modified form of engine, taken on a plane at right angles to the crank shaft.

Fig. 11 is a view in side elevation indicating by dotted lines the interior parts shown in Fig. 10 as viewed from the right hand side of said Fig. 10.

Fig. 12 is a broken detail view in section on the line 12, 12, Fig. 10.

Fig. 13 is a detached detail view in vertical section of a piston showing a modified arrangement of mechanically operated intake puppet valve and its operating connections.

Fig. 14 is a view similar to Fig. 13, show-

ing a tubular balanced mechanically operated intake valve and its operated connections.

Fig. 15 is a vertical central sectional view 5 showing my invention applied to a governor controlled type of engine and showing the parts in the positions occupied thereby at the beginning of the scavenging operation.

Fig. 16 is a similar view showing the 10 parts in their positions at the beginning of the fuel charges injection.

The same part is designated by the same reference character or numeral, wherever it occurs throughout the several views.

15 I will now describe various constructions adapted for use in carrying out my invention and in attaining the above noted and other beneficial and advantageous results.

Referring specifically to Fig. 1, numeral 1 20 designates the engine cylinder within which operates the hollow piston 3. At its upper end the cylinder is provided with an enlarged chamber 1^b preferably having its interior walls of hollow sphere contour.

25 This chamber I will refer to as the explosion chamber, the interior of the cylinder 1 opening thereto, as shown. At its lower end and arranged to be uncovered by the piston 3 while still in motion on its working 30 or explosion stroke but as it arrives at the end of said stroke, the cylinder 1 is formed with a series of exhaust port openings A, which coöperate with an exhaust channel 1^a, the latter opening to the outer air in any 35 convenient manner. The piston 3 may be connected to the crank 5 by any suitable or convenient connecting rod. The crank 5 operates in the closed chamber of a casing 7, which constitutes a storage chamber

40 into which atmospheric air is compressed and in which said air is recompressed by an enlargement 4, carried at the lower end of piston 3, and constituting an auxiliary piston which recompresses the air in the storage chamber of casing 7 during the working 45 or explosion stroke of the piston. The casing is provided with an enlarged portion 25 within which the auxiliary piston 4 works and which constitutes a primary chamber

50 having as an outer wall the outer portion of casing 7, and an inner wall provided by piston 3 during the explosion or working stroke into which primary chamber atmospheric air is drawn during the working stroke of the piston 3, and is initially compressed by the auxiliary piston 4 during the compression stroke of the piston 3. From this chamber 25, the compressed air is delivered into the storage chamber of casing 7 during and at

55 the end of the compression stroke of pistons 3 and 4, as will be presently more fully explained, and there recompressed during the next working stroke of the pistons 3 and 4, as above stated, by the auxiliary piston 4. Operating within chamber 25, is a longitudu-

dinally reciprocable sleeve 6, having at its upper end a series of port openings 6^a, formed therethrough and which are arranged in circular line with each other. These port openings coöperate with two series of port openings B and C, the former admitting atmospheric air to the auxiliary chamber 25, during the working or explosion stroke of the piston 3, and the latter admitting the air which is compressed in the chamber 25 during the compression stroke of the piston, to the chamber of casing 7, through by-passes 26, 27. These by-passes may be located at any desired point. In the form shown they are placed at opposite sides of the engine. When the sleeve 6 is shifted in one direction its port openings 6^a are brought into register with the series of ports B to admit atmospheric air to the chamber 25, and when said sleeve is shifted in the opposite direction the ports 6^a are brought into register with the series of ports C, to permit the compressed air contained in chamber 25, to pass through the by-passes 26, 27, into the chamber of casing 7. The auxiliary piston 4 is provided with passages 4^a which come into register with the ports C as the piston 3 approaches the end of its compression stroke, thereby permitting the compressed air contained in chamber 25 to continue to pass into the storage chamber till the compression stroke of the piston is completed.

At its lower end the sleeve 6 controls two series of port openings D, D¹, which respectively communicate with the by-passes 26, 27, the ports D being located in line with each other and in proximity to but in a horizontal plane below the line of ports D¹. With this arrangement it will be noted that upon the upward movement of the sleeve 6, the ports D are the first to be opened to admit the compressed and recompressed air contained in the storage chamber to by-pass 26, and then the ports D¹ will be opened to admit the compressed air to the by-pass 27.

As above stated the piston 3 is hollow. At its upper end it is provided with two sets of port openings 3^a 3^c, through the wall thereof respectively designed and arranged to coöperate with ports 4^b, 4^c, which are respectively associated with the by-passes 26, 27. The piston ports 3^a, are arranged in transverse line with each other and in proximity to but in a horizontal plane slightly above the transverse line of the ports 3^c. The ports 4^b, 4^c, are in the same horizontal plane, and are located below the large exhaust ports A, A¹. With this arrangement it will be seen that in the position of the parts as shown in Fig. 1 with the piston in its lowest position ready to begin its compression stroke, the ports 3^a and 4^b are in register with each other, so that when the sleeve 6 is moved upwardly a distance suffi-

130

cient to uncover the port openings D, the compressed air in the storage chamber of casing 7 will pass from said chamber through the ports D, by-pass 26, ports 4^B, and ports 3^A, into the hollow piston 3. When however, the piston 3 begins its compression stroke the port openings 3^A, pass above the port openings 4^B, and the port openings 3^C will be brought into register with port openings 4^C. By this time the sleeve 6 will have been moved sufficiently to uncover the port openings D¹, and then the path of the compressed air in the chamber of casing 7 is open through said ports D¹, by-pass 27, the fuel feed device, presently to be described, and the ports 4^C, piston ports 3^C to the interior of piston 3. The piston 3 is provided with passages 3^B, 3^D, respectively in communication with the ports 3^A, 3^C, and 20 are normally closed by a valve 3^E, yieldingly held to its seat by any convenient means, shown in this instance as a spring 28. In the form of my invention shown in Figs. 1, 2 and 3, the valve 3^E unseats upwardly by 25 the pressure of the compressed air admitted, as above explained, through the ports 3^A, 3^C, thereby admitting the air under pressure, and the air and fuel under pressure as the case may be into the cylinder 1.

30 The sleeve 6 may be operated in any suitable manner. In the form shown in Figs. 1, 2 and 3, said sleeve is operated by an eccentric 5^A on the crank shaft 29, and a strap connection 5^B, actuated thereby.

35 I have referred to the by-pass 27, as co-operating with a fuel feed. The feed of the oil or gas supply is accomplished through a connection 30, which, together with the by-pass 27, is controlled by an outwardly seating spring pressed valve 31, in a fitting 32, with which the ports 4^C are in communication. With this arrangement it will be seen that when the ports D¹ are uncovered and the ports C closed, the compressed air from 40 the chamber of casing 7, passes from said chamber into the by-pass 27, past the fuel supply connection 30, drawing the fuel supply along with it, lifts valve 31, passes into chamber 32, and thence through ports 4^C, and 3^C, when the latter are in register with the ports 4^C, and through passage 3^D, lifting valve 3^E, and on into cylinder 1. At the time this operation takes place the piston 3 has moved a sufficient distance in its 45 compression stroke to close the exhaust ports A, Fig. 2 shows the position of the parts corresponding to the operation just described. The piston 3 continuing in its compression stroke closes the ports 4^C, and compresses 50 the charge, the latter being fired at the limit of the compression stroke. Fig. 3 shows the parts in their respective positions, corresponding to the completion of the compression stroke of the piston.

55 In Figs. 8, 7 and 6, I have shown the rela-

tive positions of the crank and the operating eccentric for the sleeve 6, corresponding to the positions of the parts shown in Figs. 1, 2 and 3, respectively.

The operation is as follows, commencing with the parts in the position shown in Fig. 1: As shown, air under pressure is being admitted to the cylinder 1 from the chamber of casing 7, through ports D, by-pass 26, ports 4^B, ports 3^A, channel 3^B of the piston 3, and valve 3^E. This is the scavenging blast. The stream of air entering cylinder 1, centrally and at the lower end thereof, strikes the inner surface of the end wall of enlarged chamber 1^B, and is deflected backwardly by the curved contour of the inner surface of said chamber 1^B, thereby thoroughly driving out the products of combustion of the immediately preceding explosion through the enlarged exhaust ports A, which at this time, is in register with the exhaust passage 1^A. Not only does this blast effect a thorough scavenging of the explosion chamber and cylinder, but it also serves to fill said chamber and cylinder with fresh atmospheric air under pressure, and to cool the same. The piston now begins its compression stroke and the eccentric 5^A begins to shift the sleeve 6. The piston movement causes the port openings 3^A to be carried out of register with ports 4^B, thereby cutting off the fresh air blast through passage 26. The continued upward movement of the piston then closes the exhaust ports A and causes ports 3^C to be brought into register with the ports 4^C, while the movement of sleeve 6, causes ports D¹ to be uncovered, whereupon the compressed air escapes in a blast from the chamber of casing 7, through ports D¹, passage 27, past the fuel supply connection 30, through valve 31, fitting 32, ports 4^C, ports 3^C, piston passage 3^D, and valve 3^E, in the cylinder 1. The cutting off of the exhaust left the cylinder and explosion chamber filled with fresh air under pressure. This is augmented by the blast of fresh air and fuel admitted as just described, thereby supplying the cylinder and explosion chamber with the charge for the next explosion. By reason of the explosion chamber 1^B being of enlarged area I am enabled to secure an increased volume of fuel for each explosive charge, and consequently a greater driving power for the piston when the explosion takes place.

After the fuel charge is admitted to the cylinder and explosion chamber as above explained, the piston continues on its compression stroke travel which carries the ports 3^C out of register with the fuel inlet ports 4^C, and then the compression of the explosive charge takes place up to the point where the explosion occurs.

During the compressing stroke of the piston 3, the atmospheric air which was drawn

into the chamber 25, through ports B and 6^A, on the immediately preceding working stroke of the piston is compressed in the chamber 25 until, at the proper time, the 5 sleeve 6 is shifted to bring the ports 6^A into register with ports C¹, whereupon the compressed air passes through the by-pass 26 into the chamber of casing 7. The escape 10 of air from chamber 25 to the chamber of casing 7 continues to the full end of the compression stroke of the piston by reason of the passages 4^A in the auxiliary piston 4.

In Fig. 3 the piston is shown in its limit of compression stroke. The explosion now 15 takes place and the piston begins its working stroke during which the air contained in the chamber of casing 7, already under pressure is still further compressed by the piston, while fresh atmospheric air is drawn 20 into chamber 25. The explosive force of the explosion continues to exert its power upon the piston until it very nearly reaches the limit of its working stroke and uncovers the ports A. Immediately thereafter the 25 sleeve 6 is shifted to uncover ports D, and the piston ports 3^A are brought into register with the ports 4^C, thereby permitting the scavenging blast to be delivered into the cylinder as above described.

30 In the construction above described, and as shown in Figs. 1, 2, and 3, the valve 3^E which controls the admission of compressed air into the cylinder to scavenge the cylinder and the explosion chamber and which 35 also controls the admission of the compressed air and fuel to form the explosive charge, is automatically unseated by the air pressure against the action of a tension spring. This arrangement and manner of 40 operating the valve may be departed from without affecting the spirit of my invention in its broadest scope. In Figs. 10 and 11, I have shown means for mechanically operating the piston valve. In this construction 45 the cylinder and piston and the port arrangements remain essentially the same as above described with reference to Figs. 1, 2, and 3. In Figs. 10 and 11, I have omitted 50 illustration of the by-passes and the fuel supply connection and fitting for the sake of clearness.

In the arrangement shown in these views of the drawing the valve 3^E is mounted and operated as follows: Said valve is held to 55 its seat by a spring 35 which acts against a collar 36, on the stem of the valve. Carried by the end of said stem is a roller 37, which rests upon a yoke 38. This yoke extends transversely across the bore of the hollow 60 piston and is movably supported at each end from depending brackets 39, 40, by pins 41, which engage elongated curved slots 42 in the ends of the yoke. The stem of valve 3^E is raised, and said valve is unseated 65 positively and against the action of spring 35,

whenever yoke 38 is rocked, and whether said yoke is rocked about the supporting pin 41 of one end or the other end. Whenever the motion of the engine is reversed, levers 43 and 44 change action, the active 70 lever becoming inactive, and the other, which was inactive becomes active, thereby providing the necessary mechanical action for the lifting of the intake valve in the piston at right time for that reversed motion. The arrangement shown in Figs. 10 and 11, for accomplishing this result includes levers 43, 44, pivotally mounted intermediate their ends on ears 45, carried by a collar 46, mounted on the pin 47, which connects the piston 3 with the piston rod 8. The ears 45 are located at opposite sides of the pin 47, whereby the upper ends of the levers 43, 44, are arranged to be rocked into and out of engaging relation with respect 85 to the respective ends of yoke 38. The levers 43, 44, are normally urged in any convenient manner into position for the upper ends thereof to engage the ends of the yoke, I have indicated tension springs 48, for this 90 purpose. These levers may be rocked against the tension of said springs to carry the ends thereof into inactive relation with respect to said yoke in any suitable or convenient manner, as for instance by the arrangement of the piston rod with the stop screw 50, which are made adjustable in order to properly time the valve operations. I have shown a simple arrangement for the 95 purposes of controlling the levers 43, 44, according to the direction of operation of the engine, wherein I employ a rocker lever 49, which, when rocked in one direction forces one of said levers 43, 44, into withdrawn or inactive relation with respect to 100 yoke 38, and, at the same time, permits the spring 48 of the other of said levers to rock said lever into engaging relation with respect to said yoke. A rod 51, telescoped through a tubular sleeve 52, when the piston descends has its free end arranged to 105 engage the rocker lever 49, and rock the same.

In Figs. 13 and 14, slightly different arrangements are shown for mechanically unseating the piston valve. In the arrangement of Fig. 13, the valve with its stem and roller 37, its tension spring 35 and collar 36, remain the same as in Fig. 10. Instead, however, of employing a yoke 110 pivoted at both ends with two operating levers therefor, I have shown in Fig. 13 only the yoke 53 as pivoted at one end only, as on a pin 54 in the end of a bracket 55, the roller 37 on the end of the valve stem resting upon said yoke 53. The free end of said yoke is arranged to be engaged by one 115 end of a lever 56, pivoted at 57, on an ear 58, similar to the arrangement of lever 44 in Fig. 10, and similarly provided with an 120

125

130

adjustable stop screw 59, which is engaged by the piston rod at the proper time to force the operating end of said lever 56 into withdrawn or inactive position.

5 In Fig. 14 a different construction of valve 60 is shown, which is itself in the form of a tubular stationary piston fitting inside of a movable sleeve 61. A coil spring 102, is interposed between the end of the sleeve 61 and the balanced valve 60, and said movable sleeve carries a roller or other engaging device 63, which rests upon a yoke lever 64, pivotally connected at one end to a pin 65, on a standard 66. The lever 56, and its associated parts and the method of its operation all remain the same as above described with reference to Fig. 13.

In Figs. 10, 11 and 12, I have shown a modified arrangement for operating the valve sleeve 6, and for securing reversals in the direction of operation of the engine. In this arrangement a spiral gear 67, on the engine shaft, drives a shiftable spiral gear 68, which, in turn, engages and drives a 25 spiral gear 69, on a short counter shaft 70, upon which is mounted the eccentric 71, and strap 72, for rocking a lever connection 73, to the valve sleeve 6. The intermediate spiral gear 68 is mounted to be shifted upon 30 a stub shaft 74 whereby, by shifting said spiral gear into a different circumferential engagement with spiral gears 67, 69, and into proper relation for the reversal of the action of the sleeve 6, a reversal of the engine is effected.

In Figs. 15 and 16, I have shown my invention applied to a governor controlled type of engine, Fig. 15 showing the parts in their respective positions at the point of beginning of the scavenging operation and Fig. 16 showing the parts in their respective positions at the point of beginning the fuel supply to the engine. Engines of the governor controlled type do not require accumulative air pressure at stated intervals as do engines of the variable speed type and consequently the tubular air controlling sleeve valve 6, shown in the other views of the drawing is dispensed with in the type 45 of engine shown in Figs. 15 and 16, thereby reducing the constructional cost.

Referring specifically to Figs. 15 and 16, the piston 75, operates in the cylinder 1, the latter exhausting through exhaust ports A 55 and channel 1^A, as in the arrangement shown in the other views of the drawings. The piston is provided with the enlarged part 76, which aids in drawing atmospheric air into the crank case compression chamber 77, through spring seated inwardly unseating valve 78, on the up stroke of the piston and compresses the air in said chamber on the down stroke of the piston. A port 79, communicates from said chamber 60 to a by-pass 80, in which is located a con-

trol valve 81, said by-pass coöperating through ports 82, with the piston port or passage 83, and valve 84, to permit the passage of the compressed air from the compression chamber into the cylinder for 70 scavenging purposes. The piston passage 75 73 is shown in Fig. 15 as just arriving in communication with the ports 82. The by-pass control valve 81, may be periodically operated in any convenient manner. A simple arrangement is shown wherein said valve is cylindrical with a transverse passage therethrough, and is mounted to move rotatively. It is provided with a crank arm 85, to which is connected a rod 86, 80 which is projected endwise against the tension of a spring 87, by means of a cam 88, on the engine shaft. The valve 81, is opened at the time the piston port 83, arrives in communication with ports 82, thereby admitting the compressed air to the cylinder for the purpose of scavenging the same and filling it with clean fresh air. On the opposite side of the engine a by-pass 89 communicates with the compression chamber 90 77, through ports 90, said by-pass being controlled by a valve 91, operated by a cam 92 on the engine shaft in precisely the same way that valve 81 in the by pass 80 is operated. During the scavenging operation, 95 however, the valve 91 remains closed. Communicating with the by-pass 89 is a fuel feed connection 93, and a valve 94, seating toward the by-pass and yieldingly held to its seat, controls the communication of the 100 by-pass 89 and the fuel feed connection 93, to ports 95, with which coöperate the piston passage 96 and valve 84, to control the supply of fuel and air to the cylinder.

In order to secure the best results in scavenging the cylinder after an explosion, and in order to more perfectly effect an efficient mixture of the fuel and air supplied to the cylinder to form the explosive charge for the next succeeding explosion, I propose to 105 employ means whereby the blast of air under pressure delivered to the cylinder to scavenge it, and also the blast of air and fuel to form the explosive mixture, be given a swirling motion when delivered into the 110 cylinder. I have shown a simple arrangement for accomplishing this, wherein the upper end of the piston is continued somewhat above the intake valve 3^E, 60, 84, thereby forming in effect a short tubular extension 115 105, at the upper end of the piston, and within this tubular extension, and extending transversely across the bore thereof is a deflector plate 106, inclined to the vertical. This arrangement imparts to the 120 air or to the air and oil, a swirling motion as they enter the cylinder.

The upper end of the casing 107 in which the sleeve 6 operates is shaped with a downwardly extending portion 108, and the 130

auxiliary piston or head 4 of the main piston 3 is correspondingly shaped as indicated at 109. The result of this arrangement is that the complete exhaust of compressed air from chamber 25, is facilitated and accomplished by the head 4 during the compression stroke of the piston.

Having now set forth the objects and nature of my invention, and various constructions embodying the principles thereof, what I claim as new and useful and of my own invention, and desire to secure by Letters Patent, is,—

1. In an explosive engine, a cylinder and piston, said piston having passages uniting in a common delivery opening into the cylinder, means for delivering air under pressure and an explosive charge in successive order through said passages and common delivery opening, and mechanically operated means for controlling said opening.
2. In an explosive engine a cylinder and piston, said cylinder having exhaust ports at one end, said piston arranged to uncover said ports as it approaches the limit of its working stroke and having passages therethrough, said passages uniting in a common delivery opening in said piston, said common delivery opening delivering into said cylinder from the piston and means for supplying air under pressure at the same time said ports are opened and mechanically operated means for controlling said delivery.
3. In an explosive engine, a cylinder and piston, said cylinder having exhaust ports at one end thereof said piston arranged to uncover said ports as it approaches the limit of its working stroke, and having passages uniting in a common delivery opening into the cylinder, a mechanically operated valve for controlling said opening and means for supplying air under pressure and an explosive charge to said respective passages in successive order the air under pressure being supplied simultaneously with the opening of said ports.
4. In an explosive engine, a cylinder and piston said cylinder having exhaust ports at one end thereof, said piston arranged to uncover said ports as it approaches the limit of its working stroke, and having passages uniting in a common delivery opening into the cylinder, a valve for controlling said opening, means for operating said valve, and means for supplying air under pressure and an explosive charge respectively to said passages in successive order the air under pressure being supplied simultaneously with the opening of said ports.
5. In an explosive engine, a cylinder and piston, said piston having an enlarged portion, a chamber in which said enlarged portion works, said chamber having air inlet and delivery ports, means for controlling said ports whereby air is drawn into said

chamber, compressed therein and delivered therefrom, a storage chamber to which said delivery ports deliver, by-passes delivering from said storage chamber to the cylinder said port controlling means controlling said by-passes.

6. In an explosive engine, a cylinder and piston, said piston having an enlarged portion, a chamber in which said enlarged portion works, said chamber having air inlet and delivery ports, whereby air is drawn into said chamber, compressed therein and delivered therefrom, a storage chamber to which said delivery ports deliver, said piston also operating in connection with said storage chamber to recompress the air therein, by-passes delivering from said storage chamber to the cylinder, said piston also operating to open said by-passes to the cylinder in successive order.

7. In an explosive engine, a cylinder and piston, said piston having an enlarged portion, a chamber in which said enlarged portion operates, said chamber having air inlet and delivery ports, means for controlling said ports whereby air is drawn into said chamber, compressed therein and delivered therefrom, a storage chamber included in said engine to which said delivery ports deliver, said piston also operating in connection with said storage chamber to recompress the air therein, by-passes delivering from said storage chamber to the cylinder, said port controlling means also serving to open said by-passes to the cylinder in successive order, and a fuel supply connection communicating with one of said by-passes.

8. In an explosive engine, a cylinder and piston said piston having passages therethrough delivering centrally into the cylinder, a mechanically operated valve controlling said passages, and means for supplying air under pressure and an explosive charge in successive order to the cylinder through said passages.

9. In an internal combustion engine, a cylinder and piston, an intake valve in the piston, a spring normally operating to maintain said valve seated, a lifting member to engage and unseat said valve against the action of the spring a fulcrumed lever to actuate said lifting member said fulcrumed lever arranged to be moved into active position with respect to said lifting member, and in proper timed relation, by the operation of the piston.

10. In an internal combustion engine, a cylinder and piston, a connecting rod connected to said piston, an intake valve in the piston, a spring arranged to normally maintain the valve seated, a lifting bar to unseat said valve, a lever pivotally mounted intermediate its ends, and having one end arranged to coöperate with said lifting bar

- and the other end arranged to be engaged at the proper times by the connecting rod to lift said bar and unseat the valve. 50
11. In an internal combustion engine, a cylinder and piston, a connecting rod, an intake valve carried by the piston, a spring to normally maintain said valve seated, a lifting bar to unseat the valve, a lever pivotally mounted intermediate its ends and having one end movable into and out of position to operate said bar to unseat the valve, the other end of said lever arranged to be engaged periodically by the connecting rod, and means for adjustably regulating the 15 point in the stroke where said connecting rod engages said lever. 60
12. In an internal combustion engine, a cylinder and piston, a connecting rod, a spring seated intake valve carried by the piston, a movable lifting member for unseating said valve, levers pivotally mounted and respectively arranged to engage the ends of said lifting member to operate the same, said levers arranged on opposite sides 25 of the connecting rod to be engaged thereby, when in operation, a latch device to retain one or the other of said levers out of engaging relation with respect to said connecting rod and lifting member; and means 30 to operate said latch device into engaging relation with one or the other of said levers. 70
13. In an explosive engine, a cylinder having exhaust ports, a piston operating in the cylinder, said ports being opened as the piston approaches the limit of its working stroke, said piston having passages delivering into the cylinder, a compression chamber in connection with which said piston operates, admission ports located in the cylinder adjacent the end of the working stroke of the piston and beyond the end of the exhaust ports, said admission ports communicating with the compression chamber, 40 the piston passages arranged to communicate in successive order on opposite sides with said admission ports, said piston closing one set of ports when the other set is 45
- in communication with one of said piston passages. 55
14. In an explosive engine, a cylinder and piston, an air chamber and a storage chamber in communication with each other, said air chamber communicating with the outer air, a tubular sleeve valve arranged in said air chamber to control said communications, said piston having an enlarged portion arranged to work in said air chamber, bypasses delivering from the storage chamber to the cylinder and controlled by said tubular sleeve valve to allow successive fuel and scavenging charges into said cylinder and means for operating said tubular sleeve valve. 60
15. In an internal combustion engine comprising an upper water jacketed cylinder having a lower extension, a lower cylinder of larger diameter than the outer circumference of the upper cylinder spaced from the extension to form an annular recess between the outer surface of the lower portion of the upper cylinder and the inner surface of the upper portion of the lower cylinder, and a reciprocating sleeve valve mounted to slide in the recess. 65
16. An internal combustion engine comprising an upper water jacketed cylinder having a lower extension, a lower cylinder of larger diameter than the outer circumference of the upper cylinder spaced from the extension to form an annular recess between the outer surface of the lower portion of the upper cylinder and the inner surface of the upper portion of the lower cylinder, a reciprocating sleeve mounted to slide in the recess, and means for exhausting the air from the recess. 70
- In testimony whereof I have hereunto set my hand in the presence of the subscribing witnesses, on this fourth day of December, 90
A. D. 1913.
